UNITED STATES PATENT OFFICE.

DANIEL BAKER DIMICK, OF BIRMINGHAM, ALABAMA.

APPARATUS FOR CASTING PIPE.

Application filed January 31, 1924. Serial No. 689,810.

To all whom it may concern:

Be it known that I, DANIEL BAKER DIMICK, a citizen of the United States, residing at Birmingham, in the county of Jefferson and State of Alabama, have invented certain new and useful Improvements in Apparatus for Casting Pipe; and I do hereby declare the following to be a full, clear, and exact description of the invention, such 10 as will enable others skilled in the art to which it appertains to make and use the same.

The present invention relates to improvements in apparatus for casting pipe, and 15 consists in certain improvements over the apparatus illustrated and described in my copending application, Serial #588,649, filed September 16, 1922.

In the application aforesaid, the sand was 20 jolt-rammed into the mold at opposite sides of the spirally corrugated pattern, but certain difficulties arose from this method of ramming, consisting principally in the fact that it was found impracticable to properly 25 ram the mold on the under sides of the corrugations. The more the mold was jolted, the greater was the tendency of the sand to travel downward from the under inner curved surfaces of the corrugations. On the 30 top and on the sides of the corrugations, a perfect ram was secured, but upon the under portions, the sand was found to be soft. Various methods of silting in the sand during jolting were experimented with without 35 a great deal of success however.

This condition in the ramming of the mold is, however, successfully met by the process of sand slinging. A Beardsley sand slinger, which is a well known machine recently put 40 upon the market, is employed, which has a capacity of approximately 1800 handfulls of sand a minute, and this device throws the sand into the mold with great rapidity, and I find in actual practice that this method is 45 accomplished with the desired result so far as the uniform packing of the sand on the under sides of the corrugations is concerned.

Another object of the invention consists in providing a flexible connection between 50 the driving head and the corrugated pattern instead of the rigid connection as proposed in my prior application above referred to.

A further new development consists in providing the pattern with a number of 55 small pins distributed throughout a relatively short section thereof for the purpose

of roughing the sand. It is found that with the plain corrugated cylinder, the act of unscrewing this out of the sand leaves the sand in a highly slick or polished condition, so 60 much so that the iron will not lay quietly against the polished sand. The result has been that the casting is more or less worm-eaten or honeycombed.

With the foregoing and other objects in 65 view, the invention will be more fully described hereinafter, and will be more particularly pointed out in the claims appended hereto.

In the drawings, wherein like symbols refer to like or corresponding parts throughout the several views,

Figure 1 is a side elevation with parts in section showing an apparatus constructed in accordance with the present invention with 75 a Beardsley sand slinger indicated in dotted lines.

Figure 2 is a side elevation, on an enlarged scale, of the pattern and driving head.

Figure 3 is a longitudinal section taken through the parts shown in Figure 2.

Figure 4 is a bottom plan view of the driving head.

Figure 5 is a cross section taken on the 85 line 5—5 in Figure 3, and

Figure 6 is an enlarged fragmentary section taken through that portion of the pattern which contains the roughing pins.

Referring more particularly to the drawings, the apparatus is more particularly described in my copending application referred to above, and the illustration in Figure 1, together with the following description, will be adequate for the purpose of the 95 present disclosure.

The frame of the machine is indicated at 7, and an over-hanging head 8 is provided in which is carried the threaded shaft 9. The nut 10 travels up and down upon the 100 threaded shaft 9, and lifts and lowers the pattern 11 therewith. A driving head 12 is carried by the nut 10, and is coupled to the pattern 11. The pattern is provided with a spirally corrugated wall as indicated in 105 Figures 2 and 3, the pattern being a complete elongated cylinder adapted to fit down vertically into the sand within the mold indicated at 13.

The mold is carried upon a table 14 to 110 which it may be affixed by the pins 15 or other appropriate means. The table 14 is

provided at its underside with a bevel circular series of teeth 16, which mesh with the drive pinion 17. This latter pinion is turned through a shaft 18 journaled in an appropriate part of the mechanism and being connected to a suitable source of power, such for instance, as an electric motor, which is preferably independent of the electric motor 19 which drives the pattern up and down.

10 The Beardsley sand slinger is indicated in dotted lines, and when ramming the mold, it is preferable to either move the entire apparatus including the frame or standard 7 away from the mold 13, or to move the mold 15 and its rotary base from beneath the head 12. The Beardsley machine is employed to throw sand on both sides of the corrugated pattern 11, and the pattern, therefore, forms a continuously cylindrical spiral cavity in 20 the sand when removed, both interior and exterior walls of which are corrugated.

As above referred to, the method of sand slinging packs the sand uniformly not only on the tops and sides of the corrugations 25 of the pattern 11, but also on the underside thereof.

The pattern is raised and simultaneously turned after the ramming is complete in order to screw it out of the cylindrical corrugated cavity in the sand produced by it. 30 This is accomplished by the machine through the driving head 12.

The top of the pattern 11 and the driving head 12 is modified to some extent over like 35 parts in prior application. In this case the pattern is provided with a thickened collar portion 20, adapted to fit rather loosely within the inner and outer annular flanges or rings 21 and 22 upon the lower part of 40 the driving head 12. The rings 21 and 22 of the driving head are reinforced at proper points, and at these points are made registering perforations 23 for receiving the pins 24, the pins passing in through the perforations in both the rings 21 and 22 and alining 45 perforations in the pattern collar 20. Preferably, only two pins at diametrically opposite points are inserted, and as aforesaid, there is a certain looseness in the fit of the collar within the rings. This secures the 50 very desirable result of permitting the pattern 11 to adjust itself to a correct position with respect to the mold and the sand therein, and the mold will be unaffected by any 55 variations in movement of the driving head or the shaft 9. In this manner, a truer mold cavity is produced.

Now, referring more particularly to Figures 3, 5 and 6, numerous pins or small steel 60 picks 25 are shown as fitted through appropriate openings made in the wall of the pattern 11 and projecting beyond the interior wall thereof, where the same are sharpened. These pins or picks are preferably arranged in off-set or staggered rela-

tion, and they are placed at only a small cylindrical section of the pattern 11, preferably a short distance up from the base of the pattern. The function of these pins is to rough the slick or polished sand. 70

In the operation of the device, the sand slinger is caused to throw in the sand to the mold about the pattern during the rotation of the pattern on the table 14, which table preferably rotates on ball bearings and 75 is very true. The table turns at the rate of approximately eight revolutions per minute. The compactness of the ram can be regulated in three ways, namely, speed of the revolving table, speed of the sand slinger 80 motor, and rate of feed of sand into the hopper of the sand slinging machine. It requires about two minutes to throw the sand into the mold to complete the operation. The entire operation is mechanical and a 85 perfect ram on all parts of the corrugations or threads is obtained.

The pattern is then screwed upwardly and out of the sand, being driven by the pins 24 of the head 12, the connection being a flexible 90 one as heretofore described. During this movement of the pattern, the pins 25 will "rough up" the polished and slick sand, without, however, materially disturbing this sand, and the lower section of the pattern 95 will tend to press back this roughed sand, but it will not slick or polish it.

The motors for lifting and lowering the pattern and for driving the table are controlled by appropriate switches and control 100 boxes, but as these form no part of the present invention, they are not illustrated.

After the pattern is withdrawn, the molten metal is poured into the mold, and a relatively thin walled continuously cylindrical 105 corrugated cast pipe is produced, all in a single operation without any joints.

It is obvious that various changes and modifications may be made in the details of construction and design of the above specifically described embodiment of this invention without departing from the spirit thereof, such changes and modifications being restricted only by the scope of the 110 following claims.

What is claimed is:

1. In an apparatus for casting pipe, a driving head and a continuously cylindrical and corrugated pattern adapted to be simultaneously lifted and rotated out of a continuously cylindrical cavity in the sand in 120 a mold by said driving head, and means for flexibly supporting the pattern from said driving head.

2. In an apparatus for casting pipe, a 125 driving head having a substantially annular recess at its lower end, a pattern having a collar, flexibly fitted within said recess, and pins adapted to pass through the driving head and said collar to flexibly support the 130

pattern to permit it to accommodate itself to the mold and sand while being rotated and lifted by said means.

3. An apparatus for casting pipe, a vertically reciprocating and rotating head, means for lifting and lowering and for rotating said head, said head provided with internally and externally spaced rings at its lower portion, a pattern having a continuously spiral corrugation therearound

provided with a collar adapted to loosely fit in the space between said rings, said rings and collar having registering perforations at substantially diametrically opposite points, and pins adapted to pass removably through said aligned perforations for the purpose of flexibly supporting the pattern from the head, but causing said pattern to rotate and rise with the head.

DANIEL BAKER DIMICK.
